UNITED STATES PATENT OFFICE.

LOUIS JUDELSOHN, OF NEW YORK, N. Y.

CLOTHES WRINGER.

Application filed February 24, 1926. Serial No. 90,259.

This invention relates to clothes wringers and more particularly is directed to improvements in safety devices therefor.

One object of the invention is to provide a practical safety device of improved construction for a clothes wringer, said device serving to safeguard the operator from injury.

Another object of the invention is to provide an improved device of the character described which will prevent the feeding of an excessive quantity of clothes to the wringer rolls and thereby prevent possible injury to the wringer mechanism.

15 A further object of the invention is to provide an improved device of the character described which is of simple and rugged construction, which shall be comparatively cheap to manufacture, easily applied to 20 wringers of various makes, and practical and efficient to a high degree for the purposes described.

Other objects of this invention will in part be obvious and in part hereinafter 25 pointed out.

Certain features herein shown and described are shown, described and claimed in my co-pending application #24,931, filed April 22, 1922 and accordingly are not 30 claimed herein.

With the above exception the invention accordingly consists in the features of construction, combinations of elements and arrangement of parts which will be exemplified in the construction hereinafter described and of which the scope of application will be indicated in the following claims.

In the accompanying drawing, in which is 40 shown one of the various possible illustrative embodiments of this invention.

Fig. 1 is a front elevational view of a wringer equipped with a safety guard embodying the invention;

45 Fig. 2 is a cross-sectional view taken on lines 2—2 in Fig. 1;

Fig. 3 is a fragmentary plan view of the improved guard showing the mounting means therefor; and

50 Fig. 4 is a perspective view of the improved safety guard.

Referring in detail to the drawing, 10 indicates a wringer machine which may be of any standard construction and is here

seen to consist of upright standards 11 fastened to a suitable supporting base 12 and a cross member 13 normally secured for movement between said upright standards 11, as shown in Fig. 2.

The standards 11 carry gear casings 14 in each of which is housed a pair of gears (indicated in dotted lines at 15 and 16 in Fig. 1). The lower gears 15 are mounted on a horizontal drive shaft 17 which turns in fixed bearings 18 in the standards 11. 65 The shaft 17 may have at one end an extension 17^a for coupling to a power drive of any suitable well known construction (not shown).

Supported above the shaft 17 is an upper 70 shaft 19 journaled in pairs of vertically moving bearing blocks 20 mounted over the bearings 18 in the standards 11.

The shafts 17 and 19 carry the usual co-acting rubber rolls 21 and 22 respectively 75 between which the material to be wrung is inserted. The bearing blocks 20 are provided each with a tension spring 25, the upper ends of which are preferably engaged with the cross member 13.

For tensioning the rollers 21 and 22, pressure is applied, in any well known suitable manner to the cross bar, as by an adjusting screw 28, only a fragmentary portion of which is shown in Fig. 1.

80 A safety device embodying the invention is mounted on the wringer 10 to prevent accidental insertion of the operator's fingers between the rolls 21 and 22 and also to prevent the feeding of an excessive quantity of 90 clothes to said rolls and thereby eliminate possible injury to the wringer.

Said device comprises a demountable guard member 24 which may be supported by the wringer frame in any suitable manner, as in the brackets or slides 23 secured to the front and rear sides of the gear casings 14 by rivets 25^a or by other suitable fastening means. Said member 24 may be made of any suitable material and is preferably molded to form a unitary structure comprising an elongated flat front side 24^b having the ends thereof formed to extend rearwardly from said front side as at 24^c and having lugs 24^d projecting outwardly 100 from the ends of said member 24 for engaging in the brackets or slides 23.

From Figs. 1 and 2, it is seen that when

the safety device is mounted in effective position, the front side 24^a thereof extends across the wringer in spaced relation from the feeding side of the wringer rolls.

The front wall 24^a has a slot 24^d extending lengthwise thereof in alignment with the contacting surfaces of the wringer rolls. The upper and lower longitudinal rim portions of said slot are extended toward the rolls from said side to form the upper and lower flanged walls 30^a and 30^b, respectively, of the funnel shaped passage 30. The lower wall 30^a is preferably extended so as to bring the free edge portion 30^c thereof adjacent the roller 21 below the line of contact of the two wringer rolls. The upper wall 30^b is disposed above said line of contact and is made slightly narrower than said lower wall to allow for the adjusting of and the take-up wear of said rolls.

It is thus seen that the passage 30 is positioned with respect to the rolls so that the material inserted in said passage will be guided for proper feeding through the wringer.

The passage 30 is preferably flared in the direction of the front side 24^a so that the clothes being fed therethrough are squeezed preparatory to being fed between the rolls, the device thus serving as an auxiliary means for removing the moisture from the clothes.

It is apparent that the shape of said passage will greatly aid in clearing the machine should any clothes become entangled or clogged between the wringer rolls, since by reversing the feeding rotation of said rolls the clothes will be quickly released by being forced back through the flared passage towards the larger end thereof.

In using the invention, the safety device is detachably mounted in the brackets or slides 23 on the feeding side of the wringer rolls, as shown in full lines in Fig. 1. When the opposite side of the wringer rolls is used as the feeding side, the device is demounted and secured in the position shown in the dotted lines. The rolls are then rotated and the clothes fed through the wringer through the passage 30.

The front side 24^a and the passage 30 not only serve as a guard for the operator's fingers, but also shield the rolls from accidental contact with injurious objects and eliminate the possibility of any undesirable material entering between the rolls.

The demountable construction for connecting the safety device to the wringer permits ready disassembling of the wringer for cleaning, adjusting or repairing.

It will thus be seen that there is provided a device in which the several objects of this invention are achieved and which is well

adapted to meet the conditions of practical use.

As various possible embodiments might be made of the above invention and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:—

1. In combination with a pair of wringer rolls arranged for vertical rolling contact, a safety device for said rolls, said device having a passage aligned with said rolls where-through the clothes may be fed to the rolls, one wall of the passage sloping upwardly toward the lower roll to extend adjacent to and spaced so as to be just short for contacting with the lower roll below the line of contact of said rolls, and the other wall disposed above said line of contact, as and for the purpose described and specified.

2. In combination with a pair of wringer rolls arranged for rolling contact, a safety device for said rolls, said device having a passage aligned with said rolls where-through the clothes may be fed to the rolls, the walls of said passage being flared outwardly with respect to said rolls, one of said walls sloping upwardly to extend adjacent one of the rolls, and means to detachably secure the device to the wringer.

3. In a device of the character described, in combination, a wringer having wringer rolls arranged for rolling contact, a safety device for said rolls, said device having a passage aligned with said rolls where-through the clothes may be fed to the rolls, one wall of said passage sloping upwardly to extend adjacent to and spaced so as to be just short of contacting one of the rolls below the line of contact, and the other wall disposed above said line of contact, lugs extending from said device and slides for engaging said lugs to detachably secure said device to the wringer, as and for the purpose described and specified.

4. A safety device for a wringer comprising a one-piece structure having a front wall member formed with a slot therein, the rim portion of said slot being extended to form a flared passage having a wall projecting inwardly and upwardly from said front wall member to the rolls of the wringer, and lugs extending from the ends of said wall member adapted to detachably engage in slides on the wringer.

In testimony whereof I affix my signature.

LOUIS JUDELSON.
